REFRIGERATION

William R. Hainsworth, Larchmont, N. Y., assignor to Electrolux Servel Corporation, New York, N. Y., a corporation of Delaware

Application June 7, 1933, Serial No. 674,627

5 Claims. (Cl. 62—95)

This invention relates to a cooling element for a system which produces refrigeration by the evaporation of liquid cooling fluid by diffusion into an auxiliary pressure equalizing gas and 5 more particularly to a cooling element generally of the type disclosed in an application by Albert R. Thomas, Serial No. 645,432.

The cooling element disclosed in said application is of the coil type having a portion defining 10 a low temperature chamber for freezing ice cubes and the like and a portion thereabove at a higher temperature adapted for cooling air in the storage compartment of a refrigerator. Liquid refrigerant is admitted at the upper end of the coil 15 and flows in a continuously downward path through the coil evaporating by diffusion into an auxiliary gas which is circulated upwardly through the coil, the two-temperature effect being obtained due to the greater partial pressure of refrigerant vapor in the gas in the upper part of 20 the coil.

In accordance with the present invention there is provided a two-temperature cooling element of the coil type having the higher temperature portion uppermost in which the liquid refrigerant and auxiliary gas flow in the same direction through the coil.

The invention will be more fully understood by reference to the following description taken in 30 connection with the accompanying drawing, in which

Fig. 1 is a side elevation of a cooling element embodying the invention; and

Fig. 2, a front end view of the cooling element 35 shown in Fig. 1.

Referring to the drawing, a tray receptacle 10 open at the front end and having tray supports or shelves 11 is formed by an integral casting of good thermal conductive material such as aluminum. Around the closed sides of the receptacle 10 40 is a pipe coil 12 comprising a plurality of substantially horizontal superposed U-shaped turns between which are vertical reversed turns on each side of the receptacle. As best shown in Fig. 2 the coil 12 has a continuously downward slant 45 such that liquid cooling fluid introduced at the upper end of the coil will have a continuously downward path of flow therethrough.

The lower end of the coil 12 is connected 50 through an extension 13 to the upper end of a closed tube 14 which extends rearwardly with a slightly downward slant from above the front end of the receptacle 10. The exterior of the tube 14 is provided with a plurality of heat transfer fins 15 and preferably the inner surface of

both tube 14 and coil 20 is lined with capillary material such as steel mesh for retaining liquid refrigerant with an extensive surface presented to the auxiliary gas as fully set forth in the above mentioned application of A. R. Thomas.

In operation, inert gas such as hydrogen is circulated downwardly through coil 12, through extension 13, and downwardly through tube 14 from a suitable refrigeration system, connections to which are made by the upper end 16 of the coil 12 and conduit 17 from the lower end of the tube 14. Liquid cooling fluid such as ammonia is introduced into the upper end of tube 14 through a conduit 18 and flows downwardly through tube 14, liquid drain connections 19, and coil 12 due to the continuously downward slant of the tube and coil described above, and evaporates by diffusion into the hydrogen. A conduit 20 from the lower end of the coil 12 is provided for draining unevaporated liquid back to the refrigeration system.

In the cooling unit described above the hydrogen and ammonia flow in the same direction through both the tube 14 and coil 12. However, due to the lower partial pressure of ammonia vapor in coil 12 than in tube 14 evaporation in the latter occurs at a higher temperature than in the coil wherefore freezing of ice cubes and the like may be accomplished rapidly at a low temperature by heat transfer to the coil, and air in the 80 refrigerator storage compartment cooled by passage over the extensive surfaces of the tube 14 which are at a temperature above freezing. The finned tube 14 is the highest part of the coil and may therefore be located in the uppermost 85 part of the storage compartment where accumulates the warmest air, cooling of which is accomplished without the usual formation of frost due to the above-freezing temperature of the cooling 90 surface.

It will be obvious to those skilled in the art 95 that various other changes may be made in the construction and arrangement without departing from the spirit of the invention and therefore the invention is not limited to what is shown in the drawing and described in the specification but only as indicated in the following claims.

I claim:

1. A cooling element comprising, a pipe coil 105 adapted for downward circulation of inert gas and continuously downward flow of liquid therethrough, a conduit above said coil also adapted for circulation of gas and continuously downward flow of liquid therethrough, the lower end of said coil being connected to the upper end 110

of said conduit for circulation of gas therethrough in series, a liquid drain connection from the lower end of said conduit to the upper end of said coil, and a connection for supply of liquid 5 cooling fluid to the upper end of said conduit.

2. A cooling element comprising, a first conduit adapted for downward circulation of inert gas and continuously downward flow of liquid therethrough, a second similar conduit above 10 said first conduit having extensive heat transfer surfaces, the lower end of said first conduit being connected to the upper end of said second conduit for circulation of gas therethrough in series, a liquid drain connection from the lower 15 end of said second conduit to the upper end of said first conduit, and a connection for supply of liquid cooling fluid to the upper end of said second conduit.

3. A cooling element comprising, a pipe coil 20 adapted for downward circulation of inert gas and continuously downward flow of liquid therethrough, a heat conducting support for objects to be cooled in thermal conductive relation with said coil, a conduit above said coil provided with 25 extensive heat transfer surfaces and also adapted for downward circulation of inert gas and continuously downward flow of liquid therethrough, the lower end of said coil being connected to the upper end of said conduit for circulation of gas 30 therethrough in series respectively, and a connec-

tion for supplying liquid cooling fluid to the upper end of said conduit.

4. A cooling element comprising, a pipe coil having upper and lower sections both adapted for downward flow of inert gas and continuously downward flow of liquid therethrough, the lower end of the lower coil section being connected to the upper end of the upper coil section for circulation of gas therethrough in series, a connection for liquid from the lower end of said upper coil section to the upper end of said lower coil section, and a connection for supplying liquid cooling fluid to the upper end of said upper section. 80

5. A cooling element comprising, a coil having upper and lower sections both adapted for downward circulation of inert gas and continuously downward flow of liquid therethrough, said upper coil section having extensive heat transfer surfaces, a heat conducting support for objects to be cooled in thermal conductive relation with the lower coil section, the lower end of said lower coil section being connected to the upper end of said upper coil section for circulation of gas therethrough in series respectively, a connection for liquid from the lower end of said upper coil section to the upper end of said lower coil section; and a connection for supply of liquid cooling fluid to the upper end of said upper coil section. 85
